Primary Examiner — Jerry Shiuan-Hua Hsu*(74) Attorney, Agent, or Firm* — Morgan, Lewis & Bockius LLP(57) **CLAIM**

The ornamental design for a kayak as shown and described.

DESCRIPTION

FIG. 1 is a top perspective view of a kayak showing our new design;

FIG. 2 is a top plan view thereof;

FIG. 3 is a bottom plan view thereof;

FIG. 4 is a left-side elevational view thereof;

FIG. 5 is a right-side elevational view thereof;

FIG. 6 is a front elevational view thereof; and,

FIG. 7 is a rear elevational view thereof.

The broken lines depict portions of the kayak that form no part of the claimed design.
